UNITED STATES PATENT OFFICE.

HERBERT S. HUMPHREY, OF KALAMAZOO, MICHIGAN, ASSIGNOR TO RUUD MANUFACTURING COMPANY, OF KALAMAZOO, MICHIGAN.

WATER HEATER.

Application filed August 28, 1925. Serial No. 53,075.

This invention relates to improvements in water heaters.

The main object of this invention is to provide an improved water heater which is very simple and economical in its parts and which may be easily assembled or disassembled as occasion may require.

Objects pertaining to details and economies of construction and operation of my invention will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. 1 is a side elevation of my improved water heater.

Fig. 2 is a detail view partly in vertical central section on a line corresponding to line 2—2 of Figs. 3 and 4.

Fig. 3 is a horizontal section on a line corresponding to line 3—3 of Fig. 2.

Fig. 4 is a horizontal section on a line corresponding to line 4—4 of Figs. 1 and 2.

Fig. 5 is a detail vertical section on a line corresponding to line 5—5 of Fig. 1 showing details of the casing structure.

Fig. 6 is a detail view partially in horizontal section on a line corresponding to line 6—6 of Fig. 2.

Fig. 7 is a fragmentary perspective view of the inner casing.

Fig. 8 is a perspective view of the casing ring.

In the drawing the sectional views are taken looking in the direction of the little arrows at the ends of the section lines and similar numerals of reference indicate similar parts in all of the views.

Referring to the drawing, the base 1 is supported by suitable legs 2. This base has an upwardly projecting bead 3 at its outer edge providing a seat for the bottom casing section or member 4. The burner 5 rests upon this base, the casing section 4 and the base providing a burner housing or chamber.

The section 4 has air inlet openings 6 adjacent the lower end thereof, an inclined shell 7 being arranged above these openings

so that any condensation running down the inside of the casing is deflected from the openings.

The base 1 is provided with a drain 8. Resting upon the bottom casing section 4 is a casing ring 9 of cruciform section, the downwardly projecting vertical arm 10 of which is arranged within the casing section 4 while the outwardly projecting arm 11 thereof rests upon its upper edge. The top casing section 12 is removably mounted on this casing ring at its lower edge, resting upon the arm 11 of the ring while the upwardly projecting arm 13 of the ring projects into the casing, thus properly alining and supporting the casing section.

The top 14 rests upon the upper end of the casing 12 and is provided with a central opening 15. The top 14 also has upwardly projecting supporting members 16 for the cap 17, the cap having downwardly projecting lugs 18 engaging within the supporting member 16. The cap carries a deflector 19.

An inner casing wall 20 is provided, the lower end of which is arranged within the inwardly projecting arm 21 of the casing ring. This wall has an annular bead 22 providing a shoulder resting upon this arm of the casing ring so that the inner wall is centered and supported within the outer wall or casing. This inner wall is provided with a top section 23 having a central hole 24 therein registering with the hole 15 in the casing top 14.

The heating coil 25 has a centrally disposed return pipe 26 which is connected to the upper end 27 of the coil by a coupling 28. This coupling 28 carries a stud 29 passing through the spider 30 to receive the nut 31, the spider engaging the openings in the casing top and the inner wall top.

The coil is further supported and positioned by the discharge pipe 32 and the water inlet pipe 33, the pipe 32 being connected to the lower end of the return pipe 26 of the coil by means of the coupling 34 while the inlet pipe 33 is provided with an arm 35 engaging with the coupling, thus providing a cross member at the bottom of the coil which rests upon the casing ring 10. This casing ring is notched to receive the pipes 32 and 33.

A tie rod 36 extends downwardly from the coupling member 34 through the bottom 1 to receive the clamping nut 37. The sup-

porting web 38 for the pilot 39 on the burner has a hole therein to receive this rod; the rod, however, is removable without removing the burner when the nut 37 is disengaged.

The burner is provided with a supply pipe 40 controlled by the valve mechanism designated generally by the numeral 41 and operatively associated with the water inlet 33.

10. The water supply pipe is shown at 42, see Fig. 3. As this valve mechanism forms no part of my present invention, it is not described in detail herein.

15. The valve mechanism is connected to the pipe 33 by a coupling 43. The gas supply pipe is not illustrated.

20. In assembling, the coil and discharge and supply pipes are assembled as a unit, the tie rod 36 with the stud 39 being also a part of this unit. When the casing is assembled, the bottom section is placed upon the base and the burner put into position. A coupling 44 is provided as a part of the casing to receive the gas pipe 40 from the outside 25 of the casing.

25. The casing ring being mounted on the section 4 of the casing, the coil unit is put into position. The inner casing wall, which is notched at 45 to receive the supply and discharge pipes is set in place, the outer casing, which is also notched to engage these pipes, is put in place, the top 14 placed thereon, the spider arranged to engage the openings in the casing top and inner wall top, and the stud on the coil and the nuts 31 and 37 are engaged, which effectively centers and clamps the parts in position. The cap 17 is freely removable.

30. The parts can be disassembled merely by removing the nuts 31 and 37.

35. The parts of my improved heater are very simple and economical in structure and, as stated, may be very easily assembled or disassembled.

40. Having thus described my invention what I claim as new and desire to secure by Letters Patent is:

1. In a water heater, the combination of a base, a bottom casing section mounted on said base, a casing ring of cruciform cross section on the upper end of said bottom section, a top casing section removably mounted on said casing ring, a casing top having a central opening therein mounted on said top section, an inner wall having its lower end arranged within said casing ring and provided with a bead resting thereon whereby said inner wall is removably supported, said inner wall having a top portion with an opening therein registering with said opening in said casing top, a coil provided with a centrally disposed return pipe, horizontally disposed inlet and discharge pipes, a coupling connecting said discharge pipe to the lower end of said return pipe,

said inlet pipe being connected to the lower end of said coil and having an arm secured to said coupling whereby said pipes resting upon said casing ring constitute coil supporting members, a tie rod extending downwardly from said coupling through said base and having a nut on its lower end, said coil having a centrally disposed stud at its upper end, a spider on said stud engaging said opening in said casing top and inner wall top member, said stud being provided with a clamping nut for said spider whereby the parts are positioned and detachably secured together, and a burner arranged on said base, said tie rod being removable independently of said burner.

2. In a water heater, the combination of a base, a bottom casing section mounted on said base, a casing ring of cruciform cross section on the upper end of said bottom section, a top casing section removably mounted on said casing ring, a casing top having its lower end arranged within the inner arm of said casing ring and provided with a bead resting thereon whereby said inner wall is removably supported and centered relative to the outer casing, a coil provided with a centrally disposed return pipe, horizontally disposed inlet and discharge pipes resting on said casing ring, said casing ring and casings being slotted to receive said pipes, and a coupling connecting said discharge pipe to the lower end of said return pipe, said inlet pipe being connected to the lower end of said coil and having an arm secured to said coupling whereby said pipes resting upon said casing ring constitute coil supporting members.

3. In a water heater, the combination of a base, a bottom casing section mounted on said base, a casing ring on the upper end of said bottom section, a top casing section removably mounted on said casing ring, a casing top having a central opening therein mounted on said top section, an inner wall having a top portion with a central opening therein, a coil provided with a centrally disposed return pipe, inlet and discharge pipes, a coupling connecting said discharge pipe to the lower end of said return pipe, said inlet pipe being connected to the lower end of said coil and being secured to said coupling whereby said pipes resting upon said casing ring constitute coil supporting members, a tie rod extending downwardly from said coupling through said base and having a nut on its lower end, said coil having a centrally disposed stud at its upper end, a spider on said stud engaging said openings in said casing top and inner wall top member, said stud being provided with a clamping nut for said spider whereby the parts are positioned and detachably secured to-

gether, and a burner arranged on said base, said tie rod being removable independently of said burner.

4. In a water heater, the combination of 5 a base, a bottom casing section mounted on said base, a casing ring on the upper end of said bottom section, a top casing section removably mounted on said casing ring, a casing top mounted on said top section, an 10 inner wall removably mounted on said casing ring and having a top portion with a central opening therein, a coil provided with a centrally disposed return pipe, inlet and discharge pipes, and a coupling connecting 15 said discharge pipe to the lower end of said return pipe, said inlet pipe being connected to the lower end of said coil and being secured to said coupling, said pipes resting upon said casing ring constituting 20 coil supporting members, said casing ring and casings being slotted to receive said pipes whereby the casing parts may be separately assembled and disassembled.

5. In a water heater, the combination of 25 a base, a bottom casing section mounted on said base, a casing ring of cruciform cross section on the upper end of said bottom section, a top casing section removably mounted on said casing ring, a casing top having a central opening therein mounted on said top section, an inner wall having its lower end arranged within said casing ring and provided with a bead resting thereon whereby said inner wall is removably supported, 30 said inner wall having a top portion with an opening therein registering with said opening in said casing top, a coil provided with inlet and discharge connections constituting 35 supporting members resting on said casing ring, a tie rod connecting said coil to said base, a spider engaging said openings in said casing top and inner wall member and detachable connections for said spider to 40 said coil whereby the parts are detachably connected and positioned, and a burner mounted below said coil, said coil being removable independently of said burner.

6. In a water heater, the combination of a base, a bottom casing section mounted on 45 said base, a casing ring on the upper end of said bottom section, a top casing section removably mounted on said casing ring, a casing top having a central opening therein mounted on said top section, an inner wall 50 removably mounted on said casing ring, said inner wall having a top portion with an opening therein registering with said opening in said casing top, a coil provided with inlet and discharge connections constituting 55 supporting members resting on said casing ring, a tie rod connecting said coil to said base, a spider engaging said openings in 60 said casing top and inner wall member and detachable connections for said spider to said coil whereby the parts are detachably 65 connected and positioned, and a burner mounted below said coil, said coil being removable independently of said burner.

7. In a water heater, the combination of a base, a bottom casing section mounted on 70 said base, a top casing section removably mounted on said bottom casing sections, a casing top mounted on said top section, a coil provided with inlet and discharge connections constituting supporting members 75 carried by said bottom casing member, a tie rod connecting said coil to said base, detachable connections for said coil to said top whereby the parts are detachably connected and positioned, and a burner mounted below 80 said coil, said coil being removable independently of said burner when said tie rod is disconnected from said base and the top casing section removed.

In witness whereof I have hereunto set 85 my hand.

HERBERT S. HUMPHREY.
